ABSTRACT OF THE DISCLOSURE

A retrofocus-type wide-angle camera lens is provided in which the back focus is especially long compared to the composite focal length. The lens comprises a front lens group having a negative composite focal length and a rear lens group consisting of a cemented positive lens, a negative single lens, a composite positive meniscus lens, and a single positive lens. The lens thus provided has an aperture ratio of F/2.8 and a viewing angle of over 80° with various aberrations, coma, curvature of the field and distortion highly corrected.

This application is a continuation-in-part of my co-pending application bearing Ser. No. 611,206 filed on Dec. 27, 1966, now abandoned.

This invention relates to a retrofocus-type wide angle camera lens.

In a single lens reflex camera, the back focus of the objective lens is restricted because of the operation of the reflecting mirror, and it is necessary that the back focus (B.f.) of the objective lens of, for example, a 35 mm. camera should be longer than about 35 mm. Under such restrictions, it has been difficult to obtain a super wide angle lens because distortion and coma aberration are increased as the angle of view is increased although a retrofocus type objective lens has hitherto been used in order to obtain a wide angle objective lens whose focal length was shorter.

On the one hand, the increase in spherical aberration is not serious insofar as a wide angle lens is concerned, but the increase of astigmatism and distortion is detrimental to the quality of the image, and therefore the correction of these aberrations must be solved.

The object of the present invention is to provide a retrofocus-type wide angle lens in which astigmatism and distortion are highly corrected.

In accordance with the present invention, there is provided a retrofocus-type wide angle camera lens in which the back focus is especially long compared to the composite focal length, an aperture ratio of F/2.8 and a viewing angle of over 80° being provided and in which the various kinds of aberrations, in particular, coma, curvature of field and distortion are highly corrected.

Other objects, advantages and features of the present invention will become more apparent from the following

2

description of an illustrative embodiment in conjunction with the drawing in which

FIG. 1 is a cross-sectional view of retrofocus-type wide angle lens according to the present invention; and

FIG. 2 shows the various aberration curves of the lens illustrated in FIG. 1.

As viewed from the direction in which light rays are incident, L_1 is a negative single meniscus lens with the convex surface directed towards the object, L_2 is a positive single lens, and L_3 is a negative meniscus lens with the convex surface directed towards the object, the three lenses comprising the front group of the lens, the composite focal length of which is negative. Separated by a comparatively large air space d_8 from the lens L_3 is a cemented positive element comprising a positive lens L_4 and a negative meniscus lens L_5 . Separated by air space d_9 is a negative lens L_6 followed by a composite meniscus lens formed by a negative lens L_7 and a positive lens L_8 . A single positive lens L_9 completes the rear group.

The lens arrangement is such that the following conditions are met:

25 (1) $0.5d_9 < d_{11} < 2d_9$

(2) $\frac{n_5 - n_4}{r_8} \geq 0$

30 (3) $|r_{10}| > |r_{11}|$

(4) $\frac{n_8 - n_7}{r_{13}} < 0$

35

Where d and its subscript designate distance along the optical axis and n and its subscript designate the refractive indices designated on the drawing and hereinafter fully set forth. The present invention is characterized by the above mentioned conditions, and the gist of the present invention, resides in the fact that the composite focal length of the front group lenses L_1 to L_3 is made negative to form a virtual image of the object, the virtual image being formed at an indefinite distance by means of the group of lenses L_4 to L_8 (Tessa-type lens is provided in the opposite direction, and single convex lenses are made into a cemented lens of L_1 and L_8). By means of lens L_9 , the real image is formed at a predetermined position.

In order to obtain an image whose aberrations are highly corrected it is necessary to correct various aberrations of the first virtual image, and for that purpose, the correction of chromatic aberration is carried out by constituting lens L_1 a negative lens. Other aberrations such as spherical aberration, coma, image curving, distortion, and the like, are not highly corrected, but these aberrations are sufficiently corrected by the rear group of lenses.

The lenses L_4 , L_5 , L_6 , L_7 , L_8 and L_9 are lens groups having a positive refractive power and the groups of lenses L_4 to L_8 has a shape and refractive power nearly equal to that of the known Tessa, or triplet lens type

arranged oppositely. This aims to focus at infinity the virtual image formed by lenses L_1 to L_3 through the aid of lenses L_4 to L_8 . The lens L_8 gives a predetermined focal length to constitute the whole lens system.

A Tessa-type lens is principally a symmetrical lens type although its symmetry is somewhat deformed. The central negative lens is provided for correcting spherical aberration and axial chromatic aberration and astigmatism. For this purpose, it is most effective to place it at the central position, since the negative lens if located at the central position, has little effect on distortion and magnification chromatic aberration. Lenses L_4 to L_8 adopt this idea of the Tessa-type and this is expressed as $0.5d_9 < d_{11} < 2d_9$. With this condition, the negative lens L_8 should be placed substantially intermediate of the positive lens groups L_4 , L_5 and L_7 , L_8 .

In other words, the condition (1) is effective for producing a plane image, and it is the condition for placing the lens L_8 almost in the middle between the composite lens L_4 , L_5 an composite lens L_7 , L_8 . When so arranged, the main light rays pass through almost the center of lens L_8 (near to the optical axis), minimizing the adverse effects of astigmatism, at the same time constraining spherical aberrations. When such conditions herein proposed is changed, the main light rays pass through the periphery of L_8 (the marginal portion of lens), and not only astigmatism but also the spherical aberration is increased.

The object of the condition (2) is to correct distortion and the internal coma generated by the oblique light rays, i.e. the light rays coming into the system from the outside of the main light rays of the light coming in at a predetermined angle against the lens, such aberration being experienced in the lens systems of this kind. In other words, surface r_5 of lens L_4 is formed in the negative curved surface, and therefore the difference of the angle of incidence caused by the difference of the height of incidence of said oblique light rays, becomes larger. Thus the oblique light rays are greatly refracted and the internal coma generated by the front group of lenses L_1 to L_3 can be sufficiently corrected. If the condition is reversed, the internal coma generated in the front group of lenses is increased, and correction by the rear group of lenses becomes difficult.

Lenses L_1 , L_2 and L_3 constitute a lens group having a negative refractive power. However, when the position of the entrance pupil is behind the lens group, the negative lens has a tendency to coma aberration. In this invention, the negative lens group of L_1 , L_2 and L_3 produces internal coma aberration, which must be compensated. Condition (2) was determined for correcting the internal coma produced relative to the light rays incident at a position far away from the optical axis. The stop of the lens system according to this invention is behind the lenses L_4 and L_5 so that when the light rays pass through r_8 , the light rays receive large refraction due to the negative radius of curvature of r_5 and refractive indexes n_4 , n_5 so as to approach to the main light rays. Since the internal coma aberration of the light rays incident externally of the main light rays is caused by the refraction of said light rays in the direction deviating too much from the main light rays, the above-mentioned condition plays a role to compensate for such coma aberration.

The object of the condition (3) is to correct the internal coma generated by the aslant light rays, i.e., the light rays coming into the system from inside of the main light rays coming in at a predetermined angle against the lens. In other words, the angle of incidence of the aslant light rays onto surface r_{11} of lens L_8 is larger than the angle of incidence of the aslant light rays coming onto surface r_{10} of lens L_8 and the refraction by the surface r_{11} becomes larger than the refraction by the surface r_{10} . However, when the direction of the sign of inequality is reversed while keeping the sum of the refractive powers of r_{10} and

r_{11} constant, the change of Petzval's sum is small, and therefore the effectiveness in correcting astigmatism is decreased. The difference of refraction caused by the difference of the height of incidence of the light rays passing through lens L_8 is further decreased and therefore it is useless for the correction of the aberration.

Condition (3) is then to compensate the internal coma aberration of the light rays incident at the position nearer to the optical axis than the main light rays. In this invention, the stop is positioned intermediate of lenses L_5 and L_6 so that the light rays incident internally of the main light rays will pass lens L_6 externally of the main light rays and the height of said light rays passing through lens r_{11} becomes higher than that of the light rays passing through the lens r_{10} . Since r_{11} has a positive radius of curvature, the negative lens L_8 should bend toward the image field side, so that the light rays receive a large refraction by r_{11} to depart from the main light rays. This results in the correction of the internal coma aberration. This effect is further assured by the condition (1), i.e., $0.5d_9 < d_{11} < 2d_9$, which assures passage of the main light rays through substantially the central portion of the lens L_6 . The light path thereof is not effected too much by the bending of the lens L_6 .

The object of the condition (4) is to attain the same object and effect of the condition (3). Namely, surface r_{11} of lens L_6 corrects the internal coma of the light rays coming into the system from inside of the main light rays of the light flux coming in at a predetermined angle, but the internal coma is further corrected by the surface r_{13} between lenses L_7 , L_8 . This correction is carried out in such a manner that it increases the refractive index n_7 of the negative lens L_7 and decreases the refractive index n_8 of the lens L_8 whereby the curving in the positive direction generated on the sagittal image surface is compensated in the negative directions. If the direction of the sign of inequality is reversed, the angle of incidence of the oblique light rays becomes smaller and becomes useless for the correction of the internal coma generated in the front groups.

Condition (4) is thus determined for achieving two purposes. As is well known, it is necessary to make the refractive index n_7 of the negative lens L_7 larger than n_8 of the positive lens L_8 so as to curve the sagittal image plane toward the object side, i.e., negative. The other purpose is to compensate the internal coma aberration due to r_{11} of the light rays incident internally of the main light rays. The result of this condition is substantially the same as for r_8 , i.e., the cemented surface of lenses L_4 and L_5 .

The image of the object is formed at almost indefinite distance through lenses L_1 to L_8 when the above given conditions are satisfied, but it is not always necessary to form the image of the object at the indefinite distance. When the absolute value of the composite focal length of the lens system from L_1 to L_8 is less than twice the composite focal length of the whole lens system, and is in the positive, the composite focal length of the lens system from L_4 to L_8 becomes shorter, and the correction required becomes excessive, and the correction of aberrations difficult. On the other hand, when it is a negative value, it would be necessary for lens L_9 to have remarkably great refractive power. This also brings about poor balance, and the correction of aberration becomes difficult. Therefore, the composite focal length of the lens group from L_1 to L_8 should be preferably more than twice as much as the composite focal length of the whole lens system, and the virtual image or the real image formed at the indefinite distance can be formed as the real image at the rear of the lens by means of the lens L_9 .

As a matter of fact, in addition to the condition given above, various kinds of conventional means for correcting aberrations are employed, and as a result, a retro-focus-type wide angle camera lens, having an aperture ratio of $F/2.8$, an angle of view of over 80° , the back focus of which is over $1.5f$, and which has been highly

corrected for coma, image-surface curving and other aberrations, has been obtained.

The following are the examples of the present invention.

indices of the respective elements and $vd \dots$, the Abbe numbers for the glasses of respective elements.
